UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,123,356.

Specification of Letters Patent.

Patented Jan. 5, 1915.

Application filed February 24, 1913. Serial No. 750,126.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft yoke for railway car draft rigging having a preliminary compression resisting member.

In the drawings forming a part of this specification Figure 1 is a side elevation of a railway car draft rigging embodying my invention. Fig. 2 is a plan view, and Fig. 3 is a perspective view in half section of the rear end of the draft yoke and the preliminary compression resisting member.

Referring to the drawings 4, 4 represent draft members or parts of the car frame to which the draft rigging is attached, 5, 5 stop members provided with the front stop shoulders 6, 6 and the rear stop shoulders 7, 7.

30 The numeral 8 represents a draw bar provided with a transverse slot 9 adapted to receive a coupler key 10, which passes therethrough and through the lateral slots 11, 11 in the hollow head 12 of the draft yoke 13. 35 The slots 11, 11 are rearwardly extended to permit the movement of the key therein on buffing movement of the draw bar. The yoke 13 comprises the U-shaped strap 14 engaging at its free ends 15, 15 the yoke head 12.

40 Between the upper limb 16 and lower limb 17 of the yoke strap is disposed the compression resisting member 18, and the front and rear followers 19 and 20 respectively. 45 The limbs 16 and 17 of the yoke strap are connected at their rear end by the member 21, to which member is secured a spring cage 22, preferably by the flanges 23, 23 which engage the sides of the yoke strap.

50 The spring cage is provided with the opening 24 adapted to receive the forwardly extended springs 25, 25. The springs may be of any suitable construction, but preferably consist of two coiled springs, one nested within the other. The said springs are for-

wardly seated within the rearwardly opening recess 20^a provided in the rear follower 20. The rear follower 20 is forwardly provided with the recess 20^b to receive the head 26 of the bolt 27, which passes through the 60 said follower, the spring cage and the member 21 of the yoke strap, and is provided at its rear end with the nut 28. The recess 20^b in the rear follower 20 is of sufficient depth 65 to permit the movement therein of the said bolt head 26 on the movement of the said follower.

In normal position the rear follower 20 is spaced apart from the spring cage, as indicated at the numeral 29 in Fig. 1 of the 70 drawings. The compression resisting member 18 is located between the two followers, and on forward movement of the draw bar the draft yoke by means of the coupler key connecting the same to the draw bar is 75 drawn forwardly, compressing the springs 25 until the rear face 30 of the rear follower 20 engages the forward face 31 of the spring cage, and thereafter on the continued forward movement of the draw bar the compression resisting member 18 acts in its usual 80 manner. The springs 25 afford an easy action, and a consequent smooth and easy start of the car to which the draft rigging is applied. On buffing movement of the draw 85 bar the compression resisting member 18, being in engagement with the rear follower 20, is stopped by the shoulders 7, 7 of the stop members 5, 5 while the draw bar engages the front follower 19, which compresses the compression resisting member 18 90 in the usual manner.

I claim:

1. In a draft rigging for railway cars, in combination, a compression resisting member, a draft yoke, a draw bar slidably connected to the draft yoke, front and rear followers within said yoke, the yoke being provided at its inner rear end with a spring cage, a bolt connecting said rear follower to 100 the draft yoke, springs within said cage, the rear follower being provided at its rear face with a recess to receive said springs.

2. In a draft rigging for railway cars, the combination with a draft gear of a draw 105 bar, a yoke slidably engaging the draw bar, front and rear followers within the yoke, the yoke being provided at its inner rear end with a spring cage, preliminary springs within the spring cage, a bolt passing 110

through the draft yoke and through said springs, and having a sliding engagement with the rear follower, the said springs being forwardly seated against said rear follower.

3. In a draft rigging for railway cars, in combination, a draft yoke, a draw-bar slidably connected to the draft yoke, compression resisting means within the yoke, front and rear followers, a spring interposed between the rear end of the yoke and the rear

follower and normally spacing the rear follower from the rear end of the yoke, and a connecting member passing through said rear follower and the rear end of the yoke and slidably engaged with one of said members. 15

JOHN F. O'CONNOR.
